UNITED STATES PATENT OFFICE

WILLIAM P. GAIER, OF WICHITA, KANSAS

DOOR STRUCTURE

Application filed September 13, 1926. Serial No. 135,088.

This invention relates primarily to closures for openings but more particularly to sliding doors for vehicles. The accompanying drawings illustrate the invention as applied to the rear end of a vehicle, it being obvious, however, that in certain aspects, it is applicable to other uses, so I do not wish to be limited to the exact details shown.

Covered vehicles such as motor vehicles 10 trucks and the like usually have swinging hinged doors for covering the back of the body. These are objectionable because when they are swung to open positions that extend beyond the sides of the body, they are liable 15 to become broken. Another disadvantage is that the swinging doors have inset panels so that the surfaces of the doors are not smooth, consequently it is difficult to properly form sign letters on the rear doors. When 20 the doors become broken the repairs are relatively expensive but none of the above numbered disadvantages are present in the structure embodying my invention. As a matter of fact there is an appreciable ease in 25 manipulating the door, the subject matter of my invention, since it can easily be raised to open position. The doors constructed in accordance with my invention may be installed without sacrificing any of the cargo space 30 of the vehicle and the flat unbroken surface makes it easy to paint an artistic sign on the door. This is due to the fact that the door comprises a plurality of hinged metal panels having substantially abutting edges. The 35 panels are hinged together so that they can slide in grooves around the open edge of the vehicle body on relative short arcs, this being an advantage since the body can be made substantially rectangular to preserve the 40 cargo space.

This invention also contemplates a novel means and method for joining or hinging the several panels one to the other.

The novel features of my invention will 45 be clearly understood by the following description in connection with the accompanying drawings in which:

Fig. 1 is a fragmentary rear perspective view of a vehicle body to which my invention 50 is applied.

Fig. 2 is a perspective view of two joined sections of the door.

Fig. 3 is a cross-sectional view through a die for forming the hinged joint between two adjacent sections, the mandrel and sleeve being in positions to receive the edges of the 55 plates forming the sections.

Fig. 4 is a similar view of the forming die showing the positions of the mandrel, sleeve and plates after the hinged joint is formed, 60

Fig. 5 is a cross-sectional view showing a support for one of the guides.

The body of the vehicle may conform in general principles to any inclosing structure. It is illustrated as consisting of the sides 1 and 2, the bottom 3 and the top 4. At the rear end of the vehicle is an opening 6 adapted to be covered and uncovered by the door, to be hereinafter described. The rear end of 65 the vehicle body is provided with channel-shaped guide members 7 and 8 which extend vertically from the bottom of the vehicle body to substantially the top, to provide vertical legs 9 and 10, the guide members being provided with horizontal legs 11 and 12 connected to the vertical legs by intermediate curve portions 13 and 14, the connecting portions are curved on relatively short arcs preferably generated from the four inch radius. 70 At the curve portions, the lower flanges of the channel-shaped guides are cut away for portions of their width as indicated at 15 and 16 for a reason which will presently be apparent. It will be seen that each guide 75 7 and 8 has a vertical leg and a horizontal leg connected by a curved intermediate portion. These receive the trunnions and the edges of the panels or sections which when hinged together constitute the closure for the 80 rear opening. The panel sections are best illustrated in Fig. 2. Two panels are here shown designated 17 and 18. The panel 17 is illustrated as having an inset transparent panel 19 by means of which light may be 85 admitted into the vehicle body. In other respects the panel 17 corresponds with the panel 18. The panel 19 may be omitted in some instances or as many may be used as is 90 found expedient. Each panel is preferably 95 90

100

provided near its end edges with pressed ribs 20 and 21 which reinforce the sheet of which the panel unit consists.

The adjacent panels are hinged together by a novel method. The mechanism for carrying out the method is best illustrated in Figures 3 and 4, which consists of a split outer member or tube 22 within which is a mandrel 23 having a sheet receiving groove 24. The edges of two adjacent sheets are placed in the groove as shown in Fig. 3. Then the mandrel is turned by any appropriate mechanism in a clock-wise direction to wind the two edges in parallel relation within the space 25 between the mandrel and the sleeve. The meeting edges of the two sheets are thus wound in tubular form one upon the other, to form an interlocking hinge. The sheets may now be drawn off the mandrel and from the sleeve in interlocked engagement. The door may be made up of an appropriate number of the panel sections, the edges 26 and 27 being cut inward from the ends so as to provide projections 28, 29, 30 and 31, which extend into the grooves and constitute trunnions for the door sections. The flanges of the guides over-lap the edges 26 and 27 of the door section so that a comparatively tight closure can be made. When the door is raised to move the top sections into the horizontal legs, the flat portions of the panel sections would have a tendency to bind against the lower flanges of the curve portions of the guides. In order to prevent this binding I have cut away the lower flanges at 15 and 16 as shown in Fig. 1 retaining enough flange width to constitute a guide for the trunnion passing over it. Thus I am enabled to generate the curve of a relatively small radius. The bottom panel section may have a handle 32 and an appropriate lock may be employed if desired.

In Fig. 5 I have shown a form of securing the guide channels to the body of the vehicles. In this form an upright post 33 is provided against which a channel 34 corresponding to the channels 7 and 8 may be fastened by screws 35 or other suitable devices. The outstanding flanges 36 and 37 may be reinforced by the strips 38 and 39, which may be nailed or screwed to the post 33, the strips 38 and 39 abutting against the flanges 36 and 37, the combined width of the members 34, 38 and 39 being equal to the width of the post 33. This makes a rigid guide structure but it may not be necessarily employed under all conditions.

I may make other changes or modifications without departing from the spirit of the invention, so I reserve the right to make such changes as properly come within the scope of the appended claim.

What I claim and desire to secure by Letters-Patent is:—

In combination an inclosing vehicle body having an open rear end, spaced channel-

shaped guides within the opening, each guide having a vertical leg and a horizontal leg connected by a curved intermediate portion, the lower flange of each channel being only partly cut away at the point of curvature, the inner flanges of the remaining portions of the vertical leg and the horizontal leg of each guide thereby being wider than the cut away portion of each guide, relatively wide flat hinged panels bridging the gap between the guides, and trunnions on the hinged panels movable continuously over the lower flanges of the guides.

In testimony whereof I affix my signature.
